UNITED STATES PATENT OFFICE.

FREDERICK H. VON KELLER, OF NEW YORK, N. Y., ASSIGNEE, BY MESNE ASSIGNMENTS,
TO COOPER HEWITT ELECTRIC COMPANY, OF HOBOKEN, NEW JERSEY, A CORPORA-
TION OF NEW JERSEY.

HIGH-TENSION VAPOR-CONVERTER.

1,110,630.

Specification of Letters Patent. Patented Sept. 15, 1914.

Application filed December 5, 1905. Serial No. 220,352.

To all whom it may concern:

Be it known that I, FREDERICK H. VON KELLER, a citizen of the United States, and resident of New York, county of New York, 5 State of New York, have invented certain new and useful Improvements in High-Tension Vapor-Converters, of which the following is a specification.

The present invention relates to means whereby vapor converters may be so constructed as to be adapted for transmitting current to high potential direct current translating devices without danger of being injuriously affected by short-circuits within 10 the apparatus. I am aware that it has been proposed to provide against such injurious short-circuiting by arranging the several electrodes of a vapor converter in chambers having openings which are directed away 15 from each other. The theory upon which this construction is based is that the short-circuiting which does frequently take place in the unprotected vapor converters, especially when transmitting currents of high 20 potential, is due to the direction of a certain amount of vapor discharged from one electrode and received or accumulated by another electrode during a time when the latter is acting momentarily as a negative elec- 25 trode with relation to the former, it being known, moreover, that the fundamental theory of electro-statics requires charged particles attracted by an electric charge to pass in straight lines toward the charge, 30 unless disturbing conditions are present. It has been thought that the danger of short-circuiting in vapor converters might be avoided by interposing in the direct line between any two electrodes in the apparatus 35 an obstructing wall, as of a chamber partially inclosing one or more of the electrodes. 40

The object of the present invention is to improve upon the construction proposed as above referred to, by increasing the indirectness of the flow of particles between any two electrodes in the vapor apparatus. It is found that the question of the breaking down of either electrode through short-circuiting depends not so much upon the relative proximity of this electrode to another as upon the question whether or not the particles attracted by the said electrode are able to pass thereto through a direct or an indirect path. I have myself discovered, for

example, that without changing the relative 55 position of the electrodes in a vapor converter, I can by interposing obstructions in different ways between the said electrodes, vary between wide limits the voltage required to precipitate a short-circuit. 60

My invention is illustrated in the accompanying drawings, in which—

Figures 1, 2, 3 and 4 are elevations, partly in section, illustrating four different embodiments of the present invention. 65

Referring to the first figure of the drawing, 1 is the container of a vapor converter, 2 and 3 are the main positive electrodes thereof, the same being generally of iron or some other suitable solid material, and 4 is the main negative electrode, usually of mercury. A supplemental positive electrode, 5, also commonly of mercury is provided in a separate pocket or chamber, 6. The elements so far named are not unusual in vapor 70 converters or other forms of vapor apparatus. The novelty appearing in Fig. 1 is that whereby the electrodes 2 and 3 and the main negative electrode 4 are so protected from any direct discharge between any two 75 of the electrodes that particles seeking one or the other electrode from any given electrode would have to pass through a course involving at least two deflections or changes of direction. This results from the construction 80 of the tubular chambers, 7 and 8, surrounding the electrodes 2 and 3, respectively. In the case of a discharge from either of the main positive electrodes to the other, the number of turns or changes of direction is 85 at least five. 90

In Fig. 2 I show similar electrodes 2, 3 and 4, the latter being surrounded by a starting-band, 9, which is connected to the lead-wire, 10, extending to the electrode 3. 95

The two devices illustrated in Figs. 1 and 2 incidentally embody different methods of starting the apparatus into operation, the device of Fig. 1 being started in a well-known way by first bringing the electrodes 100 4 and 5 into contact and afterward separating them to start the flow of current. In Fig. 2, the well-known starting-band method of initiating the flow of current is illustrated in diagram. It will be seen that 105 the tubular chambers 7 and 8 are here arranged somewhat differently from the way they are shown in Fig. 1, but it will also be

seen that they are effective in instituting indirect direction of discharged particles from any one electrode to any other electrode inside the converter.

5 Still another embodiment of the invention is illustrated in Fig. 3 wherein a third solid positive electrode, 11, is shown inclosed in a separate chamber 12 having an opening, 13, indicated in dotted lines. The 10 electrodes 2 and 3 are mounted in tubular extensions, 14 and 15, respectively, of the container 1 and the whole arrangement manifestly provides against the possibility of any direct discharge from one electrode 15 to another.

A further embodiment of the apparatus is illustrated in Fig. 4 which explains itself, it being only necessary to say that the electrodes 2 and 3 are mounted in extensions 20 14 and 15 as in Fig. 3 and that the possible paths of flow of particles between any two electrodes require a plurality of turns or changes of direction.

In the drawings I have illustrated only 25 two positive electrodes in each container protected according to my invention for use upon high voltage or other circuits, but I wish it understood that my invention is applicable to any number of protected electrodes 30 suitable for connection to a source of any number of phases having an appropriate number of terminals.

The electrode, 13, is shown in Fig. 3 as

being connected by a conductor, 20, with a source, 21, of direct current, the said source 35 being joined by a conductor, 22, with the lead running to the main negative electrode, 4.

It is, of course, understood that the tubular parts, 7 and 8, inside the container are 40 not essential to the apparatus in order to make it perform the functions ascribed to it in this specification. It is only necessary that provision be made either inside or outside the container for protecting the several 45 electrodes in the manner and to the extent described herein, as will be more particularly pointed out in the claim which follows.

I claim as my invention:—

In a vapor electric apparatus, the combination of an inclosing chamber, a negative electrode, a plurality of positive electrodes, tubular inclosing chambers for the positive electrodes having their orifices directed away 55 from each other within the chamber, the portions of the tubes surrounding the electrodes being of greater cross section than the remaining portions of the tube.

Signed at New York, in the county of 60 New York, and State of New York, this 29th day of November, A. D. 1905.

FREDERICK H. von KELLER.
